CLAIM

The ornamental design for the support for batten, joist or the like, as shown and described.

DESCRIPTION

FIG. 1 is a top plan view of the support for batten, joist or the like of the ornamental design;

FIG. 2 is an isometric view from above and front of the support for batten, joist or the like of the ornamental design;

FIG. 3 is a bottom plan view of the support for batten, joist or the like of the ornamental design;

FIG. 4 is a front view of the support for batten, joist or the like of the ornamental design;

FIG. 5 is a left side view of the support for batten, joist or the like of the ornamental design; and,

FIG. 6 is a right side view of the support for batten, joist or the like of the ornamental design.

The broken line showing is for illustrative purposes only and forms no part of the claimed design.
